CARTOGRAPH

Grace A. McDonald, Petersburg, Ill.

Application November 29, 1937, Serial No. 177,131

5 Claims. (Cl. 35—41)

My invention relates to cartographs and more particularly to cartographs of the bas-relief type.

One of the principal objects of my invention is to provide a cartograph having land areas defined by actual liquid.

Another object of my invention is to provide a device of the above described character which is simple in construction, efficient in use and lends itself to the teaching of geography and history.

10 Other objects and advantages will be apparent from the following description, appended claims and annexed drawing.

Referring to the drawing wherein like reference characters designate like parts throughout the several views:

Fig. 1 is a top plan view of my invention.

Fig. 2 is a sectional view taken on a line 2—2 of Figure 1.

20 Fig. 3 is a sectional view of a modified form of plate.

In practicing my invention I provide a support frame 5 of substantially rectangular configuration having legs 6 secured to the corners thereof for supporting the frame above a floor or the like.

25 Mounted within the frame 5 is a receptacle in the form of an elongated tank 7 having an open top and a bottom 8. Vertically extending side walls 9 are provided and engage the inner faces 30 of the frame 5, said side walls having outwardly extending flanges formed at the top thereof engaging the top faces of the frame whereby the tank is supported in suspended position within the frame.

35 Secured to the bottom 8 of the tank are a plurality of vertically extending posts 10 on which is mounted a plurality of spaced plates 11, said plates being of a suitable configuration to define geographical land areas, for instance various

40 continents, islands and the like. Said plates, on the upper faces thereof, are colored to define the boundaries between the different countries on their respective continents and the like. The plates are segmented whereby to define inland

45 bodies of water, rivers, streams and the like. The tank is supplied with a liquid of sufficient depth whereby the plates 11 are maintained above the surface thereof.

The bottom 8 of the tank is formed with an outlet closed by a removable plug 12 in order that the water or liquid may be drained from the tank when desired.

50 A protective sectional cover 13 is hinged to the leg 6 and is foldable over the tank 7 as illustrated in dotted line in Figures 1 and 2. The cover is

constructed of wood or the like thereby permitting the structure to be used as a table. However, the cover may, if desired, be constructed of transparent material, for instance glass, whereby the interior of the tank may be viewed therethrough.

From the foregoing it will be apparent that the plates 11 define land areas and that the liquid forms bodies of water bounding said land areas. A map of this character permits the teachings of 10 geography and history to children in a manner whereby they can readily grasp the difference between the land areas and the bodies of water surrounding the same.

If desired models of ships and the like may be 15 employed and moved between the different land areas to illustrate trade routes and for illustrating historical journeys of various ships. The plates may be of the bas-relief type and have buildings, flags or other devices formed thereon 20 for further illustrating historical and geographical eras.

The modified form of plate illustrated in Figure 3 depicts the mountains, hills or the like as being raised above the upper surface of the 25 plate to lend a more realistic setting to the cartograph.

What I claim is:

1. A cartograph, comprising, a receptacle having a bottom, a plate mounted on and spaced 30 from said bottom and adapted to define a geographical area of land bounded by a body of water, and a body of liquid in said receptacle and contacting said plate to represent said body of water bounding said area of land.

2. A device of the character described, comprising, a receptacle having a bottom, a plurality of spaced plates supported above said bottom and adapted to define geographical areas of land bounded by a body of water, a body of liquid 40 within said receptacle and contacting said plates to represent said body of water bounding said areas of land, and means maintaining said plates spaced relative to each other.

3. A device of the character described, comprising, a support frame, a receptacle supported in said frame and having a bottom, plates mounted on and spaced from said bottom and adapted to define geographical areas of land bounded by a body of water, and a body of liquid 45 in said receptacle and contacting said plates to represent said body of water bounding said areas of land, and posts supporting said plates in spaced relation on the surface of said water.

4. A cartograph, comprising, a receptacle hav- 55

ing a bottom, a plate mounted on and spaced from said bottom and adapted to define a geographical area of land bounded by a body of water, and a body of liquid in said receptacle and contacting said plate to represent said body of water bounding said area of land, said plate having an upper face fashioned with a relief for depicting said area.

5. A device of the character described, comprising, a support frame, a receptacle supported in said frame and having a bottom, plates mount-

ed on and spaced from said bottom and adapted to define geographical areas of land bounded by a body of water, and a body of liquid in said receptacle and contacting said plates to represent said body of water bounding said areas of land, 5 and posts supporting said plates in spaced relation on the surface of said water, said plates having upper faces fashioned with reliefs for depicting said areas.

GRACE A. McDONALD. 10
